UNITED STATES PATENT OFFICE.

EDWARD L. CAUM, OF PATTERSON, PENNSYLVANIA.

IMPROVEMENT IN BUFFER AND DRAW-BAR FOR RAILROAD-CARS.

Specification forming part of Letters Patent No. 71,580, dated December 3, 1867.

To all whom it may concern:

Be it known that I, EDWARD L. CAUM, of Patterson, Juniata county, State of Pennsylvania, have invented a new and useful Combined Buffer and Draw-Bar for Railroad-Cars; and I do hereby declare the following to be a full, clear, and exact description thereof, which will enable others skilled in the art to which the invention appertains to make and use the same, reference being had to the accompanying drawing, forming part of this specification.

Figure 1 is an under-side view of a car-truck with my invention applied. Fig. 2 is a vertical longitudinal section of the same, the line *x x*, Fig. 1, indicating the plane of section.

Similar letters of reference indicate corresponding parts in the two figures.

My invention consists in a novel method of combining the draft-rods with the bumpers and a buffing apparatus, whereby to prevent the injurious shocks and strains to which the cars are subjected under the common modes of construction.

A A are parallel draft-rods situated at either side of the center plates B' B', which receive the king-bolts to connect the coach or car to the truck. These draft-rods may pass through apertures in the frame-work B of the truck, and are thus guided in rectilinear paths during the longitudinal sliding motion which they receive. They may also be supported and prevented from sagging at the center by a hanger depending from or a staple inserted into the under side of the truck; and for convenience in applying them to the car each draft-rod may be made in two parts, to be attached together at the center of the car by a bolt and jaw connection, or otherwise. At one end the rods A are provided with nuts or heads *a*, and upon their opposite ends are cut screw-threads for the reception of the nuts *a'*, by means of which the said rods are confined within and adjusted in relation to the coupling-plates C C. The rods I usually make one and one-eighth ($1\frac{1}{8}$) inch in diameter, and the parts upon which the nuts are fitted one and one-fourth ($1\frac{1}{4}$) inch in diameter. These dimensions, however, are, of course, varied according to the weight to be drawn. The holes in the plates through which the ends of the rods A pass are sufficiently large to permit said plates to move or play freely therein.

D D are the bumpers arranged to slide in guides at the ends of the frame B, and E are what may be termed "draw-bars," united to and rigidly projecting from the respective bumpers D D. These draw-bars E each pass through a hole in the middle of its corresponding plate C, and through another hole in the center of the plate F, and the draw-bars E are held therein by a head, nut, or key, as may be convenient. The motion of the plates C and F is limited in one direction by the spring G, when fully contracted, and in the opposite direction by their respective abutments *c* and *f*. (See Fig. 2.) They are held in working position by the guides *f f*. About each draw-bar E is coiled a spring, G, whose opposite ends abut against the movable plates C and F. The bumpers D are connected to those of the adjacent cars or coaches by links and pins in customary manner.

The above-described method of combining the bumpers, draw-bars, draft-rods, and buffing apparatus possesses peculiar and important advantages, and effectually subserves objects which have not hitherto been attained.

The application of springs to the running-gear to avoid shocks is not regarded as a new expedient, but antecedent devices of this character are either liable to the objection that they subject the frame-work to injurious strain in the act of drawing the cars, or expose the draft-rods to constant liability to jamming and bending when the cars come together, or they involve those injurious characters jointly. Now, with my improved draft apparatus, it will be perceived that in use the frame is not subjected to strain by applying at or near one end of the car the draft or drawing power required to move the car, (as is commonly the case,) that the cars are not liable to undue shocks in starting, stopping, or coming together, and that the draft-rods A A are not liable to be bent or jammed by force applied to their opposite ends when two or more cars are brought together. Thus, when one of the bumpers D, together with its drawbar E, is drawn forward by the engine, the power is not immediately transmitted to that end of the car, but the rods A A and rear plate C and foremost plate F are drawn forward, contracting the springs G G, and gradually applying the power to the abutment *c* at the end

of the car opposite to that where the draft is applied to the forward bumper. In this way the car is moved by a pushing action, or, in other words, impelled from the rear, which entirely obviates the dismemberment or injury which the frame undergoes when pulled at the forward end, as is commonly practiced. In backing, the same advantage arises, from the fact that the cars are likewise pushed or impelled from the front.

The cars which are coupled with and string behind the forward car are drawn entirely by the draft apparatus, and none of the weight or strain involved in drawing them is appreciated by the forward car.

When the cars come together the yielding bumpers D transfer the force to the springs G, and the plates C slide back upon the rods A, which are not subject to any bumping or jamming action whatever, said rods being shorter than the car-frame.

Having thus described my invention, what I claim as new, and desire to secure by Letters Patent, is—

The combination of the yielding bumpers D D with the sliding rods A A, when said rods are connected by the plates C C, and employed in connection with the plates E F, and bolts or draw-bars E E, and adjusted within the car-frame, and arranged to operate substantially as and for the purpose set forth.

To the above specification of my combined buffer and draw-bar for railway-cars, I have signed my hand this 31st day of August, A. D. 1867.

EDWARD L. CAUM.
